UNITED STATES PATENT OFFICE.

PETER MUSSER, OF MUSCATINE, IOWA.

LOG-DECK OF SAW-MILLS.

SPECIFICATION forming part of Letters Patent No. 252,499, dated January 17, 1882.

Application filed May 17, 1881. (Model.)

To all whom it may concern:

Be it known that I, PETER MUSSER, a citizen of the United States, residing at Muscatine, in the county of Muscatine and State of Iowa, have invented a new and useful Improvement in Log-Decks of Saw-Mills, of which the following is a specification.

My invention relates to an improvement in log-decks in which the logs are held on an inclined plane and delivered to the saw-carriage as required; and the objects of my improvements are, by means of simple and easily controlled mechanism, to hold the logs in place on the inclined plane and to deliver them to the saw-carriage from the plane as they are wanted. I attain these objects by the mechanism substantially as shown in the drawings, and hereinafter described.

Figure 1 of the drawings is a side elevation 20 of a log-deck embodying my invention, showing the logs held in position thereon by the radial arms, also the usual carriage for receiving the logs therefrom; and Fig. 2 is a top plan view of the log-deck.

25 In the accompanying drawings, A represents the inclined plane or deck on which the logs are supported and revolved. This inclined plane or log-deck, which may be of the ordinary construction, has suitably connected 30 to it a rotating shaft, C, which carries two or more sets of radially-arranged arms, B, one of said arms in each set being held at right angles to the inclined plane or deck, thus preventing the movement of the logs.

35 The mechanism I prefer to use in holding the arms in the position above indicated is as follows—viz., a sliding bar, D, controlled and moved backward or forward by a suitable lever, e, operated by hand or foot power, the 40 radial arm next behind the one holding the log striking the under side of the bar D, as shown in dotted lines, Fig. 1, thereby holding

it stationary. Upon pulling back the sliding bar D by the lever e, the log, resting against and held by the radial arms, rolls by its own 45 gravity onto the saw-carriage, and as soon as the log has turned far enough to carry the arm which was held by the bar D beyond said arm the lever is reversed and the next arm and log caught.

50 Although I have shown what I consider the most simple and practical means of holding and releasing the radial arms, I do not wish to be understood as confining myself thereto, as any suitable holding and releasing mechanism may be substituted, so long as it will hold the arms stationary, but permit a partial rotation of said arms by the weight of the log when the stop or holding mechanism is tripped or released. The radial arms and the shaft to which they 55 are connected are also susceptible of modification or change so long as the arms are capable of a rotary motion, a continuous shaft being preferably used.

Having now fully described my invention, 60 what I claim as new, and desire to secure by Letters Patent, is—

65 1. In an inclined plane or log-deck of saw-mills, the combination, with rotary arms, of a suitable stop mechanism, substantially as 70 shown, to hold said arms, but permit of their partial rotation by the weight of the log when the stop is tripped or released, substantially as and for the purpose set forth.

75 2. In an inclined plane or log-deck of a saw-mill, the combination, with rotating arms, of a stop mechanism consisting of a sliding bar operated by a suitable lever, substantially in the manner and for the purpose specified.

PETER MUSSER.
